United States Patent

Des. 242,126
Patented Nov. 2, 1976

242,126

BOTTLE OR SIMILAR ARTICLE

Maurice K. Morea, Kansas City, Mo., assignor to Ethyl
Development Corporation, Kansas City, Mo.

Filed Mar. 12, 1975, Ser. No. 557,751

Term of patent 14 years

Int. Cl. D9—01

U.S. Cl. D9—143

FIG. 3.

FIG. 1.

FIG. 2.

FIG. 4.

FIG. 5.

FIG. 1 is a front elevational view of a bottle or similar article embodying my new design;

FIG. 2 is a side elevational view thereof;

FIG. 3 is a top plan view thereof;

FIG. 4 is a bottom plan view thereof; and

FIG. 5 is a sectional view taken along section lines 5—5 in FIG. 1.

I claim:

The ornamental design for a bottle or similar article, substantially as shown.
